COMBINED SOAP HOLDER AND GRAB RAIL

Joseph P. Boughey and Julues P. Compagnucci, Trenton,
N.J., assignors to Bay Ridge Specialty Company, Inc.,
Trenton, N.J., a corporation of New Jersey

Filed Aug. 12, 1960, Ser. No. 61,727

Term of patent 14 years

(Cl. D4—3)

FIG. 1 is a top perspective view of a combined soap holder and grab rail embodying our new design;

FIG. 2 is a front elevation thereof on a reduced scale;

FIG. 3 is a top plan view thereof; and

FIG. 4 is a side elevation thereof.

We claim:

The ornamental design for a combined soap holder and grab rail, as shown.
